Primary Examiner — Brett Miller*Assistant Examiner* — Mary Anne Arntzen(74) *Attorney, Agent, or Firm* — Bartholomew Law PC; Michael Bartholomew(57) **CLAIM**

The ornamental design for a car injector cleaner and tester as shown and described.

DESCRIPTION

FIG. 1 is a front, right and top perspective view of a car injector cleaner and tester, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the car injector cleaner and tester in another state.

The broken lines depict portions of the car injector cleaner and tester that form no part of the claimed design.
